UNITED STATES PATENT OFFICE.

WESLEY H. LOWD, OF GLEN FRAZER, CALIFORNIA.

TRAIN CLASSIFICATION AND NUMBER INDICATOR.

1,354,437.

Specification of Letters Patent. Patented Sept. 28, 1920.

Application filed January 5, 1917. Serial No. 140,754.

To all whom it may concern:

Be it known that I, WESLEY H. LOWD, a citizen of the United States, residing at Glen Frazer, in the county of Contra Costa 5 and State of California, have invented certain new and useful Improvements in Train Classification and Number Indicators; and I do hereby declare the following to be a full, clear, and exact description of the invention, such as will enable others skilled in the art to which it appertains to make and use the same.

The invention relates to a train classification and number indicator.

15 The object of the present invention is to provide a simple, practical and compactly arranged train classification and number indicator of inexpensive and strong and durable construction adapted to be readily applied to locomotives, cars and the like and capable of enabling the train classification means and the number of the train to be indicated by a single device at a certain place on a train.

25 With these and other objects in view, the invention consists in the construction and novel combination of parts hereinafter fully described, illustrated in the accompanying drawing, and pointed out in the claim hereto appended; it being understood that various changes in the form, proportion, size and minor details of construction, within the scope of the claim may be resorted to without departing from the spirit or sacrificing 35 any of the advantages of the invention.

In the drawings—

Figure 1 is a perspective view of a train classification and number indicator constructed in accordance with this invention, 40 Fig. 2 is a longitudinal sectional view of the same,

Fig. 3 is a transverse sectional view of the device,

Fig. 4 is a horizontal sectional view illustrating the arrangement of the electric light and the heating means for the globe,

Fig. 5 is an enlarged vertical sectional view on the line 5—5 of Fig. 4,

Fig. 6 is a detail perspective view of one 50 of the indicator plates,

Fig. 7 is an enlarged elevation of the flag.

Like numerals of reference designate corresponding parts in the several figures of the drawings.

55 In the accompanying drawings in which is illustrated the preferred embodiment of

the invention, the train classification and number indicator comprises in its construction an oblong receptacle 1 designed to be constructed of sheet metal or other suitable material and to be secured at opposite sides of a locomotive or car of a train and any suitable means may be employed for mounting the casing either permanently or detachably in position on a train. The oblong casing or receptacle 1 which is provided with a hinged cover 2 is divided into a longitudinal series of compartments 3 by transverse partitions 4 and the casing or receptacle 1 is preferably equipped with six 60 compartments but any desired number of compartments may be employed and the said compartments contain a plurality of indicator plates 5 and one or more electric lamps may be stored in one of the compartments. The compartments containing the indicator plates are designed to be provided with longitudinally disposed partitions 8 connecting the transverse partitions and forming separate spaces or cells for the reception of the indicator plates 5. The indicator plates 5 which are preferably provided with openings 9 for the reception of hooks or other suitable means for enabling them to be readily withdrawn from the compartments. Letters or other characters as shown are applied to the plates. The plates may be arranged in front holding means 10 said means consisting of vertical ways formed by vertical strips 11 which are connected 70 by a bottom strip 12 adapted to form bottoms for the holding means for supporting the plates within the holders. The spaces between the vertical strips 10 are open at the top to enable the plates to be readily introduced into and removed from the holders and the said plates are exposed at the front of the casing or receptacle and are designed to be provided at each face with a number or letter so that by reversing them 75 either character may be presented to view at the front of the receptacle or casing. By means of the numbers, letters and other characters, the train classification and the number of the train may be indicated in a single device at a predetermined point on a train. The indicator plates preferably extend above the longitudinal partitions in order that the hook or other instrument, employed for removing the plates from the 80 compartments may be readily engaged with the perforations or openings 9 in the upper 85

portions of the said plates to remove them. Any other suitable means, however, may be employed for this purpose.

The device is provided at the front with 5 a reflector 13 located at the upper portion of the receptacle or casing and set at an angle so as to throw the light of electric lamps 14 downwardly and inwardly upon the characters of the indicator plates. The 10 reflector which is substantially semi-cylindrical in cross section is provided with a plurality of sockets 15 to receive the electric lamps and the latter may be connected in any desired manner with the lighting 15 current of a train. The reflector which is provided with end walls 16 forms a casing or housing for the electric lights and is adapted to protect the same. The reflector is connected with the outer portion of a 20 longitudinally disposed pipe 17 which is supported by brackets 18 but the reflector may be mounted in various other ways. The pipe 17 which is provided at one end with a coupling member 19 is designed to be connected with the hot air or steam pipe of 25 a train so that steam or hot air may be discharged upon the exterior of the indicator plates for removing snow and ice in cold weather. The pipe 17 is provided at the bottom with jet apertures 20 extending downwardly and inwardly and arranged to discharge upon the indicator plates as clearly 30 illustrated in Fig. 3 of the drawings.

The receptacle or casing 1 is provided at 35 one end with flag holding means consisting of a socket 21 and a loop or strap 22 located above and spaced from the socket, but a single continuous socket piece or similar device may of course be employed for this 40 purpose. The socket 21 and the loop 22 are adapted to receive the flag 7 as clearly illustrated in Fig. 1 of the drawings. The receptacle or casing is provided at the other end with an electric light 25 mounted upon 45 a horizontally projecting support 26 and arranged within a removable globe 27 which is threaded onto the socket member 28, a rubber gasket 29 being interposed between the globe or protector 27 and the support 26 50 as clearly illustrated in Fig. 5 of the drawings. The globe is adapted to be readily removed to afford access to the electric lamp which may be changed from a white one to a green one or one of another color when 55 required. The horizontal support 26 consists of a plate or member arranged at an angle to the casing and preferably extending from one corner thereof at an angle of 45 degrees and provided with a recessed 60 inner end 26^a which fits the corner.

The receptacles or casings are designed to be made in pairs or single and when in pairs they will be right hand and left hand, so that the lamps 25 will always be visible 65 on each at the forward end and the flags

7 on each will be displayed at the rear end. In practice the device is designed to be placed just back of the smoke stack with the forward end nearer the boiler than the rear end, the casing being preferably placed at 70 approximately an angle of 45 degrees to the track but they may be of course placed in any other desired position as will be readily understood.

The electric wiring and the connections 75 may be arranged so as to permit the device to be transferred from one side of a train to the other. The plates are adapted to be readily placed in and removed from the exterior holders and the pipe 17 is spaced 80 from the upper portion of the receptacle or casing to provide an opening to enable the plates to be readily introduced in and removed from the grooves or ways of the holding means.

In order to maintain the globe 27 at a 85 sufficiently high temperature to prevent it from being entirely covered with snow and sleet in winter and the electric light obscured by the same a heating tube is employed. The heating tube which may be connected with the heating pipe of a train or other suitable means for supplying a heating fluid is composed of spaced vertical portions 30 piercing the support 26 and the 90 socket member 28 and connected at the top by a curved horizontally disposed portion 31 arranged concentric with the electric light and extending partially around the same in spaced relation with the light and 95 the globe. The curved portion of the heating tube is located preferably in a position so as not to obscure the light and it may be of any desired size and length to secure the required heating effect. The lower terminals 32 of the vertical side portions 30 of the heating pipe are threaded for enabling 100 them to be coupled with suitable pipe connections.

The flag 7 which may be a train classification flag or for any other use, and which 110 may be of any desired color, preferably of two sections 33 and 34 constructed respectively of sheet metal and fabric, the sheet metal section being preferably three-fifths 115 the area of the flag and the fabric section two-fifths to prevent the fabric from wrapping around the staff 35. The sheet metal section 33 is preferably connected to the staff 35 by suitable rings 36 and the fabric 120 section is connected with the sheet metal section by rings 37 linked into suitable apertures of the sheet metal section and the fabric section. The rings 36 are also designed 125 to pass through perforations of the sheet metal section and to be removably arranged on the staff so that the latter may be changed should it become broken or otherwise injured. The fabric portion of the flag may be attached to the metallic portion 130

or section by any other suitable means and the detachable connection between the fabric portion and the metallic section will enable the fabric portion to be renewed or 5 changed as required or desired.

What is claimed is:—

An indicator comprising a casing having a sight opening located in its front side, the edges of the opening being spaced from the 10 edges of the said front side, transverse partitions arranged within the casing and forming a series of compartments, longitudinal partitions arranged within the compartments and having their upper edges disposed below the plane of the upper edges of the transverse partition and the top of the 15 casing, indicator plates arranged between

the longitudinal partitions and extending above the same and provided with openings adapted to be engaged by an implement for 20 removing them from the casing, and a reflector mounted upon the casing and located at the exterior thereof at a point in advance of the sight opening and at the upper portion thereof and directed downwardly 25 toward the said sight opening.

In testimony whereof I affix my signature in presence of witnesses.

WESLEY H. LOWD.
